ARCHITECTURAL TILE WALL

Erwin Franz Hauer, Wooding Hill Road,
Bethany, Conn. 06525

Filed Feb. 28, 1967, Ser. No. 5,993

Term of patent 14 years

(Cl. D18—2)

Fig. 1

Fig. 2 Fig. 3

I claim:

The ornamental design for an architectural tile wall, substantially as shown.
